UNITED STATES PATENT OFFICE

162,711

SINGLE ELECTRIC SHAVER IN BOX DISPLAY CASE

Harry L. Carpenter, Kalamazoo, Mich., assignor to Lawrence A. Westerberg, Skokie, Ill.

Application March 23, 1950, Serial No. 8,725

Term of patent 3½ years

(Cl. D80—11)

To all whom it may concern:

Be it known that I, Harry L. Carpenter, a citizens of the United States, residing at Kalamazoo, State of Michigan, have invented a new, original, and ornamental Design for Single Electric Shaver in Box Display Case, of which the following is a specification, reference being had to the accompanying drawing, forming a part hereof.

my new design for a single electric shaver in box display case.

I claim:

The ornamental design for a single electric shaver in box display case, as shown.

HARRY L. CARPENTER.
